UNITED STATES PATENT OFFICE.

CALVIN V. REAMS AND JAMES B. HOPKINS, OF SUISUN, CALIFORNIA, ASSIGNEES OF ONE-FOURTH TO JOSEPH R. CHADBOURNE AND ONE-FOURTH TO EDWIN J. SPARKS, BOTH OF SUISUN, CALIFORNIA.

WRENCH.

1,165,207.

Specification of Letters Patent. Patented Dec. 21, 1915.

Application filed August 21, 1915. Serial No. 46,659.

To all whom it may concern:

Be it known that we, CALVIN V. REAMS and JAMES B. HOPKINS, citizens of the United States, residing at Suisun, in the county of Solano and State of California, have invented new and useful Improvements in Wrenches, of which the following is a specification.

This invention relates to a pipe and nut wrench.

One of the objects of the present invention is to provide a simple, substantial, cheaply manufactured wrench adapted for use both as a pipe and a nut wrench, and which is so constructed that it may be operated ratchet-fashion when used.

Further objects will hereinafter appear.

The invention consists of the parts and the construction and combination of parts as hereinafter more fully described, having reference to the accompanying drawings, in which—

Figure 1 is a side elevation of the wrench, partly broken away. Fig. 2 is a plan view 25 of same, partly in section. Fig. 3 is a cross section on line 3—3 of Fig. 1.

Referring in detail to the drawings, A indicates the main stationary jaw of the wrench, 2 the shank and 3 the handle; the 30 shank and handle being preferably thick in construction to produce rigidity, but cored out at the sides, as indicated by the cross sections at 4 and 5, to eliminate weight as much as possible.

Formed integrally with the shank is a 35 guide member 6 which is provided with a longitudinally disposed, rectangular-shaped slot 7 through which the threaded shank 8 of the movable jaw 9 extends. The guide member is also slotted crosswise to permit the insertion of a nut 10, of the usual construction, which, when turned from the exterior, will move the threaded shank 8 in one direction or the other to adjust the position of the movable jaw 9.

Slidably mounted and surrounding the main shank 2 is a fork-shaped carriage 11 which is secured to the inner end of shank 8 by a screw 12, or other similar means, and 50 pivotally mounted, as at 13, in the opposite end of the carriage 11 is the movable jaw 9.

Formed on the upper side of the main jaw A is a pair of upwardly extending

guide lugs 14 between which the movable jaw extends. These lugs are provided for the purpose of guiding the movable jaw 9 when it swings about its pivot 13 and are also provided for the purpose of bracing same against side movement or lateral strains, thus relieving the pivot 13 and the connected carriage 11 from being twisted or subjected to other strains than a longitudinal pull.

Formed on the inner end of the movable jaw 9, on the opposite side of pivot 13, is an extension or lug 15, and formed on the inner end of the shank 8, in line with the lug 15 and just below same, is a supporting lug 16, between which and lug 15 is interposed a coil spring 17, said spring being held in position not only by the side walls of the carriage 11 but also by means of centering bosses 18 formed on the respective lugs. This spring is provided for the purpose of normally forcing the movable jaw 75 down into position or alignment with the stationary jaw A.

For the purpose of relieving the main pivot 13 of further strain and the weight of the jaw 9 a downwardly projecting lug 19 has been provided which normally engages the upper face of the main shank 2. The inner faces of the jaws may be provided with oppositely positioned, serrated teeth 20, where the wrench is to be used both as a pipe and nut wrench, or may be perfectly smooth and used as a nut wrench only.

In operation, the position of the movable jaw 9, with relation to the stationary jaw A, is secured by turning the nut 10 in one direction or the other. This will cause the threaded shank 8, with connected carriage 11 and jaw 9, to slide longitudinally upon the main shank, thus securing the desired adjustment or position of one jaw with relation to the other or to the pipe or nut to be turned. Weight is then applied, by means of the hand, in the direction of arrow a. This causes the jaws to grip the pipe or nut and turn same in the direction indicated. Return movement in the direction opposite to arrow a will permit the wrench to ratchet as the jaw 9 may move about pivot 13 against the tension of spring 17 into the dotted line position indicated at 22. A ratchet action is thus produced on

the return movement which is particularly desirable when tightening or unscrewing nuts or like members.

A wrench constructed as here shown is 5 rigid in construction, but at the same time is comparatively light, as both the main shank and the handle are cored out on the sides, as indicated at 24. This is also true 10 of the movable jaw with its connected threaded shank 8. The provision of the upwardly extending guide lugs 14 materially increase the strength and rigidity of the movable parts as they take up all side strain 15 or lateral movement imparted to the movable jaw, with connected carriage 11 and shank 8.

The wrench as a whole may be quickly 20 adjusted and operated, as it works ratchet-fashion and is adjusted by the single mechanism, such as the nut 10.

The materials and finish of the several 25 parts of the device are such as the experience and judgment of the manufacturer may dictate.

25 We wish it understood that various changes in form, proportions and minor details of construction may be resorted to within the scope of the appended claims, and that we do not wish to limit ourselves 30 to the specific design and construction.

Having thus described our invention, what we claim and desire to secure by Letters Patent is—

1. In a wrench, a shank provided with a 35 rigid jaw, a carriage on the shank, a threaded shank pivotally secured to the rear end of the carriage, a movable jaw having a shank which latter is pivoted between its ends to the front end of the carriage, said 40 threaded shank having a lower forwardly extending lug and said shank of the movable jaw having an upper rearwardly extending lug, a coil spring in the cut-out of the carriage engaged at its ends with said 45 lugs, and means on the main shank engaged with the threaded shank to actuate the latter, said carriage and the inner ends

of the threaded shank and movable jaw and the lugs forming a housing which completely incloses the spring. 50

2. In a wrench, a shank provided with a rigid jaw, a carriage on the shank, a threaded shank pivotally secured to the rear end of the carriage, a movable jaw having a shank which latter is pivoted between its 55 ends to the front end of the carriage, said threaded shank having a lower forwardly extending lug and said shank of the movable jaw having an upper rearwardly extending lug, a coil spring engaged at its 60 ends with said lugs, a lug extending from the inner side of the shank of the movable jaw and engageable with the main shank to relieve the pivot of said shank of the movable jaw and located adjacent the pivot of 65 the shank of the movable jaw, and means engaged with the threaded shank to actuate same.

3. In a wrench, a shank having a rigid jaw, a carriage slotted on one side and 70 mounted on said shank, a threaded shank having one end projecting into the slot of the carriage from one end of said slot and pivotally secured to the carriage, a movable jaw having a shank which latter at its 75 inner end extends into the other end of the carriage slot and is pivoted to the carriage, an upper lug on the last named shank, a lower lug on the threaded shank, a coil spring in the slot engaged at its ends with 80 said lugs, and means engaged with the threaded shank to actuate the same, said carriage and the inner ends of the threaded shank and movable jaw and the lugs forming a housing which completely incloses the 85 spring.

In testimony whereof we have hereunto set our hands in the presence of two subscribing witnesses.

CALVIN V. REAMS.
JAMES B. HOPKINS.
